UNITED STATES PATENT OFFICE.

GEORGE GEACH PARNALL, OF BRISTOL, ENGLAND.

STAND FOR GOLF CADDIE-BAGS AND THE LIKE.

1,135,464.

Specification of Letters Patent. Patented Apr. 13, 1915.

Application filed June 18, 1914. Serial No. 845,872.

To all whom it may concern:

Be it known that I, GEORGE GEACH PARNALL, a subject of the King of Great Britain, residing at 4 Leyton Villas, Hampton Road, 5 Redland, Bristol, in the county of Gloucester, England, have invented a new and useful Improved Stand for Golf Caddie-Bags and the like, of which the following is a specification.

10 My invention relates to improvements in stands for golf caddie bags and the like.

The object of my invention is to improve the construction and simplify the manipulation of golf caddie bag tripod stands.

15 My invention is illustrated by way of example in the accompanying drawings, in which—

Figures 1, 2, 3, and 4 show the tripod and 20 golf caddie bag in various positions, and Fig. 5 shows an enlarged detail view of the top bracket. Fig. 6 shows enlarged detail views of the attaching means for connecting the top bracket with the bag. Fig. 7 shows an enlarged detail view of the crosshead. 25 Fig. 8 shows a plan view of the crosshead. Fig. 9 shows an enlarged detail view of the lower end of the rearward rod and its foot and its attachment to the bag, and Fig. 10 shows a side view of the attachment of the 30 lower end of the rearward rod to the bag.

Referring now to the drawings—I fix on the interior of the front of the golf caddie bag a strip of wood or metal A adapted to 35 stiffen the bag longitudinally. Attachments B and C are fixed to the exterior of the front of the bag and to the said strip of metal or wood A. The upper attachment B is fixed about four inches below the top of the bag and is so constructed as to receive a top

40 bracket D and to removably secure same by means of a turn button to the bag. In or about the center of the top bracket D is provided a square or round aperture throughout its depth. The lower attachment C is a 45 spring clip fixed about four inches from the bottom of the bag and is constructed to receive a guide bracket E which has a slot conveniently about one-eighth of an inch from the back throughout its depth, in order to

50 admit the tongue of the spring clip C and to permit the spring clip C to hold the bracket E removably. This guide bracket E is provided near the center with a square

aperture throughout its depth, and through this aperture and also through the aperture 55 in the top bracket D I pass a rod F which is afterward referred to as the rearward rod. The top bracket D has two angularly placed lugs GG to which are hinged two rods HH. A crosshead I is provided about six inches 60 below the top bracket, and encircles the rearward rod F. The crosshead I has angularly placed faces JJ, JJ (Figs. 7 and 8) in more or less parallel planes to the lugs GG. Links KK, KK connect the faces JJ, JJ on 65 the crosshead I with the two rods HH. Interposed between the top bracket D and the crosshead I is a spring L which encircles the rearward rod F. Near the top of the rearward rod F is provided a pin M adapted 70 to prevent the rod from dropping through the top bracket D. I provide a foot N at the lower end of the rearward rod F adapted to prevent damage to golf greens or the like. Immediately below the crosshead I and partly within the rearward rod F, two springs OO are fitted, which maintain the crosshead I in a fixed position when the apparatus is in use. The said springs OO are so constructed as to admit of their 75 being depressed at will into the rearward rod F. The said rod F projects about three inches below the ends of the rod HH.

When it is desired to bring the stand into use, in conjunction with a golf caddie bag 80 and clubs, the foot N of the rearward rod F is allowed to project below the bottom of the bag (Figs. 2 and 3) and to rest upon the ground. The weight of the bag and its contents lowered toward the ground causes 85 the top bracket D to descend with the bag. The crosshead I resting on the said springs OO and remaining in a fixed position relative to the foot N of the rearward rod F causes the links KK, KK to open out the 90 two hinged rods HH as the top bracket D descends toward the crosshead I whereby the two extended rods HH form a tripod, with the rearward rod F when the rods HH are fully extended and allowed to rest on 95 the ground. The bag remains supported in the desired position (Fig. 1). Upon raising the bag and clubs and foot N from the ground, the spring L (previously compressed by the descent of the bag and the 100 top bracket D toward the crosshead I)

causes the crosshead I and rearward rod F to be pushed downward, which motion, acting upon the links KK, KK draws in toward the bag the two rods HH until the apparatus 5 assumes the position which it occupied relative to the bag, previous to the foot N of the rearward rod F being placed upon the ground.

When it is desired to put the tripod out 10 of use, but to remain on the bag, the two springs OO beneath the crosshead I are depressed, enabling the rearward rod F to be pushed upward through the top bracket, the crosshead and encircling spring, and 15 the bottom bracket, until the foot N is above and clear of the bottom of the bag. When it is desired to put the tripod again into use the sliding leg is pushed downward until the springs OO automatically project from 20 the sliding leg and maintain the crosshead in a fixed position, relatively to the sliding leg. Auxiliary to, or in lieu of the spring L encircling the rearward rod F and for the purpose of causing the rods HH to 25 assume a closed position on the bag after being extended and further to cause the rearward rods to project below the bag, I may employ spring hinges attached to the top bracket D and acting upon the afore- 30 said rods, or a spring or springs attachable to any part of the rods or connections, or such parts of the apparatus as will achieve the same effect as is produced by the spring L which encircles the rearward rod.

35 What I claim is:—

1. A tripod caddie bag stand comprising a bag, brackets fixed to said bag, a rear leg adapted to slide in said brackets and normally projecting below the bottom of the 40 bag, a plurality of legs hinged to the top bracket, a crosshead slidably mounted on said rear leg, links connecting said crosshead with said hinged legs, and means for holding said crosshead in a fixed position relatively to the rear leg and adapted to be moved into a position in which said crosshead can slide over said rear leg and the stand put out of action.

2. A tripod caddie bag stand comprising 50 a bag, brackets fixed to said bag, a rear leg adapted to slide in said brackets, and normally projecting below the bottom of the bag, a plurality of legs hinged to the top bracket, a crosshead slidably mounted on 55 said rear leg, links connecting said crosshead with said hinged legs and spring means for holding said crosshead in a fixed position relatively to the rear leg and adapted to be moved into a position in which said crosshead can slide over said rear leg.

3. A tripod caddie bag stand comprising 60 a bag, brackets fixed to said bag, a rear leg adapted to slide in said brackets and normally projecting below the bottom of the 65 bag, a plurality of legs hinged to the top bracket, a crosshead slidably mounted on said rear leg, a spiral spring encircling said rear leg between the top bracket and said crosshead and tending to press said

bag, a plurality of legs hinged to the top bracket, a crosshead slidably mounted on said rear leg, links connecting said crosshead with said hinged legs, and a plurality of springs mounted in recesses in the rear 70 leg adapted to project from said rear leg and to hold said crosshead in a fixed position relatively to said rear leg and to be pressed into their recesses to allow said crosshead to slide over said rear leg.

4. A tripod caddie bag stand comprising a bag, brackets fixed to said bag, a rear leg adapted to slide in said brackets and normally projecting below the bottom of the bag, a plurality of legs hinged to the top 80 bracket, a crosshead slidably mounted on said rear leg, a spring member arranged between one of said brackets and said crosshead tending to press said crosshead downward, links connecting said crosshead with 85 said hinged legs, and means for holding said crosshead in a fixed position relatively to the rear leg and adapted to be moved into a position in which said crosshead can slide over said rear leg.

5. A tripod caddie bag stand comprising a bag, brackets fixed to said bag, a rear leg adapted to slide in said brackets and normally projecting below the bottom of the bag, a plurality of legs hinged to the top 90 bracket, a crosshead slidably mounted on said rear leg, a spiral spring encircling said rear leg between the top bracket and said crosshead and tending to press said crosshead downward, links connecting said crosshead with said hinged legs, and means for holding said crosshead in a fixed position relatively to the rear leg and adapted to be moved into a position in which said crosshead can slide over said rear leg.

6. A tripod caddie bag stand comprising a bag, a pair of brackets, means for detachably connecting said brackets with said bag, a rear leg adapted to slide in said brackets and normally projecting below the bottom 100 of the bag, a plurality of legs hinged to the top bracket, a crosshead slidably mounted on said rear leg, links connecting said crosshead with said hinged legs, means for holding said crosshead in a fixed position relatively to the rear leg and adapted to be moved into a position in which said crosshead can slide over said rear leg and the stand put out of action.

7. A tripod caddie bag stand comprising 110 a bag, a pair of brackets, means for detachably connecting said brackets with said bag, a rear leg adapted to slide in said brackets and normally projecting below the bottom of the bag, a plurality of legs hinged to the 115 top bracket, a crosshead slidably mounted on said rear leg, a spiral spring encircling said rear leg between the top bracket and said crosshead and tending to press said crosshead downward, links connecting said 120

125

crosshead with said hinged legs and a plurality of springs mounted in recesses in the rear leg adapted to project from said rear leg and to hold said crosshead in a fixed position relatively to said rear leg and to be pressed into their recesses to allow said crosshead to slide over said rear leg.

In testimony whereof I have signed my name to the specification in the presence of two subscribing witnesses.

GEORGE GEACH PARNALL.
